UNITED STATES PATENT OFFICE.

FREDERICK BRISTOW, OF EAST ORANGE, NEW JERSEY.

LETTER AND DOCUMENT DISTRIBUTER.

1,080,888.

Specification of Letters Patent.

Patented Dec. 9, 1913.

Application filed December 12, 1912. Serial No. 736,305.

To all whom it may concern:

Be it known that I, FREDERICK BRISTOW, a citizen of the United States, residing in East Orange, county of Essex, and State of New Jersey, have made a new and useful Invention in Letter and Document Distributors, of which the following is a specification.

My invention is directed particularly to an improvement upon systems of distributing papers and documents among individuals or departments in business establishments and other institutions or places, and forms a part of a system two features of which are covered by prior inventions disclosed in Letters Patent No. 753,538, granted to me on the 1st day of March, 1904, and No. 933,156, granted to me on the 7th day of September, 1909, and has for its objects, first, to adapt devices of the kind disclosed in said patents for more general use in the distribution of such letters or documents as the inventions disclosed in said patents are designed to carry. Second, to adapt the same for use generally in places of business and in public service, where letters, bills, reports, and all such documents are designed to be transported from place to place; as, for instance, in large business corporations and in the transporting of the mail by letter carriers, messenger service and the like.

The inventions disclosed in the before-mentioned patents were more particularly designed for removably stationary use upon desks or tables, the documents or articles to be distributed being placed in compartments of the radial distributor from which compartments they were designed to be taken by a messenger and carried to their several destinations.

The present invention is an improvement upon the system for distribution and consists of a peculiarly designed bag with its interior parts so arranged that compartments are provided corresponding with the compartments in the radial distributor upon the desks or tables. Into such compartments the messenger places the papers found in the desk distributor and so carries them to their destination. Prior to the invention herein described it was the practice for the messenger to classify the papers by disposing of them between the fingers of one hand and attempting to remember the proper destinations, thus incurring liability to mis-

takes and necessitating a number of trips before the contents of the desk distributor would be entirely distributed. With the use of the device herein described all of the contents of a desk distributor may be distributed in one trip of the messenger and the liability to error is eliminated by means of the marking upon the partitions forming the compartments in the bag.

For a full and clear understanding of the invention, such as will enable others skilled in the art to construct the same reference is had to the accompanying drawings, in which,

Figure 1 is a perspective view of the invention complete in open or accessible position. Fig. 2 is a transverse section of Fig. 1 through the middle thereof, showing the device in closed and locked position ready to transport. Fig. 3 is an elevational view of one of the partitions which separates the documents or matter to be distributed so as to render it convenient for the person using the device to quickly select the letters, documents, or other matter to be distributed.

Referring now to the drawings in detail, 1 represents a base made of wood, hard rubber, or equivalent rigid material and of the proper length and width to accommodate the material to be carried therein. This base may be made of flexible materials to admit of being compressed, if desired, which would be an advantage for some sorts of service. 2 represents a relatively stiff vertical wall constituting the back of the device, the same being secured to the base at right angles thereto, and 3 a similar front vertical wall, preferably of shorter height—though not necessarily so—but of similar length, the same being pivoted to the base 1 by a leather or equivalent flexible hinge 4. 5 is a strip of leather or equivalent flexible material, extending entirely around the base 1, which acts as a bumper to protect furniture from being scratched, and also to provide a suitable finish. 6 represents flexible end pieces made preferably of strong canvas and of greater width at the top than at the bottom. These end pieces are secured to the back and front walls 2 and 3, as clearly shown. 7 represents a flexible flap which is also secured to the back wall by rivets, lacing, or any other method desired. 9 represents a shoulder strap secured to the ends of the back wall by metal hooks 8, the

parts so far described constituting a portable inclosing bag adapted to be carried on one or both shoulders of a person.

10, 10 represent a series of dividing partitions of light, stiff, flexible material which are provided at their bottoms with extensions or ears 11 having holes 12 and at their tops with additional extensions 13 located at a different longitudinal position for each 10 partition, as shown in Fig. 1, each having a tag for manipulating the same. These extensions 13 are designed for indicating thereon the especial character of the documents to be distributed, or the names of persons, divisions, or departments, for which the contents are intended. These characters, names, etc., are located on the extensions so that they will be visible to the person carrying the bag. These partitions are collectively arranged within the bag, as shown 20 in Fig. 2, and held in their respective places by a screw-bolt 15 passing through the holes 12 and secured at the back of the bottom by turning the screw-bolt 15 through the agency 25 of the head 16 and firmly securing said bolt by the screw-thread 17 thereupon.

18, Fig. 1, represents a clasp for engaging the flap 7 and thus securing the device in closed position.

30 The mode of using the device is obvious, it being apparent that the letters or materials to be distributed are placed in the various compartments between the dividing partitions, in accordance with the indications 35 of the characters, persons, or divisions on the extensions 13, so that the carrier may quickly turn said dividing partitions by the tags 14 and procure the documents it is desired to distribute.

40 This device has an especial utility in connection with large business in large business institutions embracing many departments, as department stores, manufactories and the like, or in the distribution of mail 45 by letter carriers, as will be obvious from the nature of its construction. It also has an especial utility in use upon desks and its particular form, embracing a solid bottom and a vertical stiff back, makes it possible to 50 place it upon a desk in such manner that the user can readily open the flap and place therein or remove therefrom the matter desired.

I do not limit my invention to the especial details of construction illustrated in the accompanying drawings, as obviously these details may be departed from in various ways and still come within the scope of my claims hereinafter made. I believe it is 60 broadly new with me to have devised means for transporting light matter, such as let-

ters, documents, and the like, in the nature of a collapsible bag, with removable adjustable partitions, which is adapted to be folded up and locked in compact form and 65 which when thus folded completely secures and protects the matter inclosed and the particular form of bag which I have disclosed renders it practical for the user to quickly obtain the desired documents therefrom and to greatly facilitate the distribution thereof.

Having thus described my invention what I claim and desire to secure by Letters Patent of the United States is—

75 1. A portable letter and document distributor comprising a wide stiff bottom, a stiff back wall rigidly secured along the rear edge of said wide bottom, a stiff front wall hinged along the front edge of said wide bottom, upwardly-flaring bellows ends connecting said stiff back and front walls for permitting inward and outward swing of the latter to closed and open positions about its hinged connection to the front edge of 80 said wide bottom, a plurality of partitions 85 swingingly and slidably connected to the bottom and adapted to be closely confined by the upper edge of said stiff front wall in the inner position of the latter, means for securing said stiff front wall in its inner position, and carrying means adapted to be attached to said stiff back wall.

90 2. A portable letter and document distributor comprising a wide stiff bottom provided medially with a lateral recess, a stiff back wall rigidly secured along the rear edge of said wide bottom, a stiff front wall hinged along the front edge of said wide bottom, upwardly-flaring bellows ends connecting said stiff back and front walls for permitting inward and outward swing of the latter to closed and open positions about its hinged connection to the front edge of 95 said wide bottom, a plurality of interior 10 swinging partitions adapted to be closely confined by the upper edge of said stiff front wall in the inner position of the latter, perforated ears on said partitions fitting within such bottom recess, a bolt engaging said 11 perforated ears for loosely locking said partitions in position, means for securing said stiff front wall in its inner position, and carrying means adapted to be attached to said stiff back wall.

11 In testimony whereof I have signed my name to this specification in the presence of two subscribing witnesses.

FREDERICK BRISTOW.
